G. W. HEATH.
WRECK INDICATING DEVICE.
APPLICATION FILED MAY 8, 1915.

Attorney

UNITED STATES PATENT OFFICE.

GEORGE W. HEATH, OF STONINGTON, CONNECTICUT.

WRECK-INDICATING DEVICE.

Specification of Letters Patent. Patented May 23, 1916.

1,184,180.

Application filed May 8, 1915. Serial No. 26,837.

To all whom it may concern:

Be it known that I, GEORGE W. HEATH, a citizen of the United States, residing at Stonington, in the county of New London and State of Connecticut, have invented certain new and useful Improvements in Wreck-Indicating Devices, of which the following is a specification, reference being had to the accompanying drawings.

10 This invention relates to certain improvements in wreck indicating devices and has relation more particularly to a device of this general character especially designed and adapted for use in connection with submarines; and it is an object of the invention to provide a device of this general character having novel and improved means whereby the indicating medium affords a means whereby a flexible tube may be brought to the surface for the purpose of delivering air within the submerged vessel and whereby communication may be had with the occupants of said vessel.

25 The invention consists in the details of construction and in the combination and arrangement of the several parts of my improved wreck indicating device whereby certain important advantages are attained and the device is rendered simpler, less expensive 30 and otherwise more convenient and advantageous for use, all as will be hereinafter more fully set forth.

The novel features of the invention will be carefully defined in the appended claim.

35 In order that my invention may be better understood, I will now proceed to describe the same with reference to the accompanying drawings, wherein—

Figure 1 is a sectional view illustrating a 40 wreck indicating device constructed in accordance with an embodiment of my invention; Fig. 2 is a sectional view taken substantially at right angles to that in Fig. 1, with certain parts of the invention omitted; 45 and Fig. 3 is a transverse sectional view taken through the flexible tubing.

As disclosed in the accompanying drawings, H denotes a fragment of an upper portion of the hull of a submarine or other vessel 50 set to which is suitably secured the casing 1 having coacting therewith the removable cover 2, the central portion of which being provided with an upstanding extension 3 substantially cone shape in form whereby a maximum of buoyancy is afforded to the cover member when released so that the same

will readily rise to the surface of the water and the extension 3 projects above said surface so that the floating cover may be readily discerned. Depending from the cover 60 member 2 at substantially the axial center thereof and extending within the casing is the interiorly threaded sleeve 4 with which is detachably engaged in a conventional manner the screw member 5 extending through the hull and in swivel engagement therewith, as indicated at 6, in any desired manner, and the inner extremity of the screw is provided with the operating means 7 whereby the screw may be readily disengaged from the sleeve 4 when desired by an occupant of the boat.

Rotatably supported within the casing is a flanged drum 8 having produced at a predetermined point intermediate its length the 75 depression or pocket 9 to accommodate the member 10, herein disclosed as a ring of conventional diameter, to which is secured an extremity of the flexible member 11, the opposite extremity of said member 11 being 80 suitably secured to the under surface of the cover or closure member 12. The flexible member is also disposed through the ring 14 carried by the cap 15 normally in detachable engagement with an extremity of 85 the flexible tubing 16, to be hereinafter more particularly referred to, and it is to be observed that the diameter of the ring 10 is in excess of the diameter of the ring 14. By this arrangement, it will be perceived 90 that upon release of the closure member or cover 2, the same will rise to the surface of the water and by pulling up the flexible member 11, the flexible tubing 16 may also be brought to the surface through the coaction between the rings 10 and 14, as is, it is thought, clearly apparent to those skilled in the art to which my invention appertains.

95 The flexible tubing 16 is normally wound around the flanged drum 17 rotatably supported by the rigid tubular member or pipe 18 disposed transversely of the casing 1 and extending beyond opposite sides thereof and extending within the boat, the interior extremities of the pipes having interposed 100 therein the valves 19. The flexible tubing 16 is divided longitudinally into separate compartments and the bore of the conduit or pipe 18 is divided into two passages with 105 which the compartments of the flexible tubing 16 separately communicate. The conduit or pipe 18 at a point intermediate the 110

drum 17 is provided with a coupling 20 with which the inner extremity of the flexible tubing 16 is connected, as is believed to be clearly disclosed in the accompanying drawings. The coupling 20 is a two-way coupling and is in communication with the compartments 21 positioned within the flexible tubing and extending entirely therethrough and adapted to have their outer extremities suitably connected with a pump whereby air may be forced within and exhausted from the submerged boat. Also disposed through the flexible tubing are the conductors 22 extending within the boat and adapted to have their inner extremities suitably secured to a telephone instrument while the opposite or outer extremities are adapted to be suitably connected with a telephone instrument in the possession of the rescue party. As herein disclosed, the heads of the drum 17 are connected by the spaced members 23 also spaced relative to the tubular member or pipe 18 whereby it will be perceived that the tubing 16 may be readily wound upon the drum without interference or obstruction being offered by the coupling 20. It is also to be observed that the marginal portions of the cover 2 and the extension 3 are provided with the depending flanges 24 adapted to receive therebetween the upper marginal portions of the casing 1 to afford an effective engagement of the cover with the casing.

From the foregoing description, it is thought to be obvious that a wreck indicating device constructed in accordance with my invention is of an extremely simple and comparatively inexpensive nature and is

particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

In combination with a body, a casing secured thereto exteriorly thereof and having its outer face open, a cover for the open face of the casing, an upstanding extension substantially cone-shaped in form secured to the cover, the marginal portions of the extension and the cover being provided with flanges disposed in parallel spaced relation, adapted to receive the marginal portions of the open end of the casing therebetween, a depending interiorly threaded sleeve carried by the cover member at substantially the axial center thereof, a screw member extending through the body and in suitable engagement therewith, the outer extremity of the screw member being capable of threaded engagement with the depending sleeve of the cover member, and means for rotating said screw member.

In testimony whereof I hereunto affix my signature in the presence of two witnesses.

GEORGE W. HEATH.

Witnesses:

JOHN G. WHEELER,
HENRY RHODES PALMER.
